UNITED STATES PATENT OFFICE

WILLIAM BROAD, OF BEAVER FALLS, PENNSYLVANIA, ASSIGNOR OF THREE-FOURTHS
TO HARRY E. McLAIN, OF PITTSBURGH, PENNSYLVANIA

VIBRATOR

Application filed October 19, 1926. Serial No. 142,593.

My invention relates broadly to vibrators and more specifically to vibrators adapted for massaging or medical purposes, and is in the nature of an improvement over the 5 construction disclosed in my prior Patent No. 1,234,619, issued July 24, 1917.

Vibrators of this type are commonly formed with an electro-magnet energized by alternating current or frequently interrupted 10 direct current for causing vibratory movements of an armature to which a portion of the vibrator adapted to be placed next the skin is attached. In such vibrators as have heretofore been known, as, for instance, that 15 of my prior patent above referred to, the vibrating portion which is adapted to be placed next the skin has been at least partly of flexible metal suitably affixed to a frame or casing. Short circuiting or grounding of 20 connections not infrequently occurs on the inside of the casing thereby passing an electric current through the metal skin-contacting portion with the result that the person being massaged will suffer an electric shock. 25 By the present invention there is provided an improved form of vibrator which may be safely used without fear of shock or other injuring under such conditions.

In the drawings:

30 Figure 1 is a side view partly in section, of a vibrator embodying my invention;

Figure 2 is a plan view, partly in section, of the vibrator of Figure 1 with the cover removed; and,

35 Figure 3 is a cross-sectional view on the line III—III of Figure 1, looking in the direction of the arrows.

In carrying out the present invention there may be provided a casing of any appropriate 40 shape and material, although I prefer to form it as a hollow cylinder of suitable insulating material. Attached to the casing 1 by any desired means, such, for instance, as a nut 2 cooperating with threaded sleeve 3 is a handle 4, preferably substantially radially disposed with relation to the casing, the sleeve conveniently being threaded into the handle. The handle 4 may be formed of any suitable material, such, for instance, as wood or fiber, 50 and is preferably provided with an opening

5 extending lengthwise therethrough and adapted to receive wires (not shown) for connecting the electro-magnet with any suitable source of current. One end of the casing 1 is closed by a cover 6 preferably of insulating material and held in place in any suitable manner, such as screws 7.

Interiorly disposed with relation to the casing and fastened thereto in any suitable manner as by screws 8, I provide a segmental support 9 of insulating material. Attached to the support 9 as by screws 10, is an electro-magnet 11 of any desired type. Attached to the opposite side of the support 9, as by screws 12, is a flexible member 13, which 65 adjacent its upper end is adapted to be vibrated substantially in the direction of the axis of the casing.

Carried by the free end of the flexible member 13 is an angle member 15 carrying an armature 17 for actuation by the electro-magnet 11. As is apparent from Fig. 1, the armature 17 in vibrating toward and away from the electro-magnet 11 will cause the flexible member 13 to vibrate substantially 75 at right angles thereto.

Attached to the vibrating portion of the member 13, as by screws which may be, and preferably are, the same screws 14 as are used to join the members 13 and 15, I provide a 80 pad 18 of insulating material, which pad is preferably in the shape of a disk and of such size as substantially to close the side of the casing 1 opposite the cover 6, although any desired size and shape may be used. This pad 85 is adapted if desired to contact with the person of the user as well understood in the art. The vibrator may be used as a pad underneath the body or head of a patient by reason of its flat design. A considerable saving in the 90 height of the vibrator is obtained by disposing the axis of the electromagnet parallel to the vibrating surface rather than at right angles. The flexible member 13 is so shaped as to maintain the pad spaced from the casing 95 throughout its entire area.

It will be apparent that all portions of my improved vibrator which may, at any time, come into contact with the person being massaged or with the person operating the vibra- 100

tor are perfectly insulated from the electro-magnet and the armature. Therefore should any short circuit or grounding occur within the casing, all possibility of either the operator or the patient being subjected to an electric shock or burn is removed. The advantage of this feature over vibrators heretofore known, will be readily apparent. Although the screws 7 and 8 extend outwardly to the exterior of the vibrator, all of such screws are embedded throughout their entire length in insulating material and no possibility exists whereby they may become subjected to an electric current.

15 The present construction also provides a pad 18 free to vibrate throughout its entire area by reason of its mounting on the spring 13 and the space provided between the pad and the casing. This construction is advantageous as it makes the vibration not only effective over a considerable area, but insures vibrating movements of maximum amplitude. A double striking movement or a rocking movement of the pad 18 is secured during 20 each vibrating movement, thereby doubling the effective frequency of the vibrator. As the armature 17 is drawn toward the electro-magnet 11 the edge of the pad 18, directly over the support 9, is tipped upwardly a sufficient amount to impart a distinct blow to the 25 surface engaging the pad 18. A second blow is delivered when the armature 17 is released from the electromagnet 11, and the armature-carrying or forward edge of the pad 18 moves 30 outwardly under the force of spring 13.

35 While I have shown and described herein a preferred embodiment of my invention, it is to be understood that it is susceptible of numerous other applications and is not limited in any manner save by the scope of the 40 following claims.

I claim:

45 1. A vibrator, comprising a casing of insulating material, a cover of insulating material closing said casing on one side, a support within said casing, an electro-magnet attached to said support, a resilient member attached to said support, an armature adapted to be vibrated by said electro-magnet carried by said resilient member and a vibrating 50 member of insulating material actuated by said resilient member and adapted to substantially close the side of said casing opposite said cover, so that the exterior of said device 55 is composed substantially in its entirety of insulating material.

60 2. A vibrator, comprising a casing of insulating material having substantially an open side, a hollow handle of insulating material attached to said casing, an electro-magnet firmly mounted within the casing, the electric connections to which are adapted to pass through said handle, a resilient metal member secured to said casing, an armature on 65 said resilient member adapted to be vibrated

70 by said electro-magnet, and a substantially flat vibrating member of insulating material on said resilient member so disposed as to substantially close the open side of said casing.

75 3. A vibrator, comprising a casing of insulating material, a support within the casing and near one edge thereof, an electro-magnet connected to the support, a resilient member connected externally of the support, an armature carried by said resilient member and adapted to be vibrated by said electromagnet, and a vibrating member of insulating material supported by the resilient member externally of the casing and constituting a cover 80 therefor.

85 4. In a vibrating device, a casing, a vibrating member substantially closing one side of the casing, an electromagnet mounted in the casing in a plane substantially parallel to the plane of the vibrating member, an armature for the electromagnet movable with the vibrating member, and resilient supporting means for the vibrating member and armature, the supporting means being of a length 90 at least as great as half the width of the casing and attached to the vibrating member beyond the center of the vibrator and being curved, whereby diametrically opposite portions of the vibrator are caused to oscillate 95 about a line extending substantially through the center of the vibrating member and at substantially right angles to the axis of the supporting means.

100 5. In a vibrator, a casing, a vibrating member mounted on the casing and substantially closing one side thereof, resilient supporting means extending substantially from one portion of the casing across the center thereof and secured to the vibrating member beyond the center of the casing, and means for imparting vibratory movement to the vibrating member, whereby diametrically opposite edges of the vibrator are caused to oscillate 105 about a line substantially in the center of the vibrating member and at right angles to the axis of the supporting means.

110 6. In a vibrating device, a casing, a vibrating member, means for actuating the vibrating member, and a resilient support for the vibrating member extending from one side of the casing across the center thereof having the vibrating member attached intermediate its connection with the casing and the point of application of the vibrating force, whereby 115 the edges of the vibrating member are free to oscillate about a plane extending substantially through the center of the casing.

120 7. In a vibrator, a casing, a cover for substantially closing a side thereof, means for securing the cover, and means for imparting an oscillatory movement to the cover about an axis extending substantially through a diameter thereof.

125 8. A vibrator comprising a casing having 130

one open side, a combined vibrator and closure member for said casing substantially closing said side and having all points in its outer surface lying at all times beyond the 5 plane of said open side, and means for imparting oscillatory movements to said member.

9. A vibrator comprising a casing having an open side, means for closing the open side 10 constituting an applicator, means for supporting the closing means, and means for imparting an oscillatory movement to the closing means about an axis extending substantially parallel to the outer face thereof 15 and within the space defined by said outer face and the casing.

In testimony whereof I have hereunto set my hand.

WILLIAM BROAD.
